UNITED STATES PATENT OFFICE

MORTON L. PATERSON, OF BOSTON, MASSACHUSETTS, ASSIGNOR TO CONVERSE RUBBER COMPANY, OF MALDEN, MASSACHUSETTS, A CORPORATION OF MASSACHUSETTS

DESIGN FOR A SHOE SOLE

Application filed June 27, 1929. Serial No. 31,843. Term of patent 14 years.

To all whom it may concern:

Be it known that I, MORTON L. PATERSON, a citizen of the United States of America, residing at 30 Bay State Road, in the city of Boston, county of Suffolk, and Commonwealth of Massachusetts, have invented a new, original, and ornamental Design for Shoe Soles, of which the following is a specification, reference being had to the accompanying drawing, forming a part thereof.

In said drawings:

Fig. 1 is a plan view of a shoe sole showing my new design; and Figs. 2, 3 and 4 respectively are sectional views on lines 2—2, 3—3, and 4—4 of Fig. 1.

I claim:

The ornamental design for a shoe sole substantially as shown.

Signed by me at Boston, in the county of Suffolk and Commonwealth of Massachusetts this 24th day of June, 1929.

MORTON L. PATERSON.
